UNITED STATES PATENT OFFICE

136,996

DESIGN FOR A FOLDABLE, FABRIC, LUGGAGE BAG

Virginia Blake, Miami Beach, Fla.

Application February 2, 1943, Serial No. 109,411

Term of patent 7 years

To all whom it may concern:

Be it known that I, Virginia Blake, citizen of the United States, residing in Miami Beach, county of Dade, and State of Florida, have invented a new, original, and ornamental Design for a Foldable, Fabric, Luggage Bag, of which the following is a specification, reference being had to the accompanying drawing, forming part thereof.

Fig. 1 is a perspective view of the foldable, fabric, luggage bag in extended position showing my new design; and,

Fig. 2 is a perspective view of the bag in collapsed or folded position.

I claim:

The original design for a foldable, fabric, luggage bag, substantially as shown.

VIRGINIA BLAKE.
